UNITED STATES PATENT OFFICE

SOLOMON EDWARD AARON, OF BOSTON, MASSACHUSETTS

BILGE PUMP

Application filed July 11, 1929. Serial No. 377,579.

This invention relates to improvements in means for relieving the bilge of boats or vessels of the gasoline vapors and other undesirable liquids which may accumulate therein.

5 One of the prime objects of this invention is to provide a means for drawing gases from any part of the boat without shifting any of the suction elements, such as hose and the like.

10 Another object of this invention is to provide a device for creating three different suction, at three distinct points in the boat, and to render each of these suction useful at the will of the operator.

15 Other objects of this invention will appear from the following detailed description of the device as disclosed in the single sheet of drawings, which is herewith made a part of this application.

20 In the drawings—

Figure 1 illustrates a longitudinal cross-sectional view of a boat disclosing the bilge pumping system installed therein.

25 Figure 2 is a top plan of a boat partly broken away.

Figure 3 illustrates to an enlarged scale a vertical cross-sectional view of a portion of the bilge pumping system, showing the main features connected therewith.

30 Figure 4 represents one modification of the means for giving reciprocating motion to the pump plunger.

Figure 5 illustrates a cross-sectional view of the pump plunger and cylinder in open communication with the main passage, and disclosing check valves therein.

35 As one modification of this invention, it is preferred that number 1 designate the shell or outer portion of a boat, which may be of any size or type, in which this system of bilge pumping could be used to advantage, particularly in the case of a motor boat, in which a great many explosions are caused by the engine back-firing, owing to the use of improper mixture, and where in many instances the gasoline has been supplied or obtained by the opening of a carburetor and the filling of a small can with the gasoline for use in priming the engine and for like purposes.

The gasoline tank 2 is usually located in the bow of the boat 1, and sometimes in filling the tank 2 a certain amount of gasoline is allowed to drip or spill, and seeps into the timbers of the boat and, therefore, cannot be removed and functions to leave dangerous fumes in that particular location. The same conditions apply to a more or less extent in the stern of the boat where the engine 3, pump and plunger element 4 are usually located.

45 This invention relates primarily to a device or system for eliminating or pumping the fumes, vapors and liquids from three distinct points in the boat 1, that is at the bow and stern and near the center thereof, as clearly disclosed in Figure 1 at 5, 6 and 7. The object is to arrange the suction elements in such a manner that they will function through one ejector as clearly disclosed in Figure 3 wherein number 8 designates an ejector casing having a pressure inlet passage 9 for the actuating stream, a suction passage 10 for the entrained stream, and an outlet 11 for the combined actuating and entrained stream. The pressure inlet passage 9 is provided with an inlet orifice 12 through which the water under pressure enters from any suitable source, such for instance as a line 13 leading in open communication through an opening 14 in the shell of the boat 1, thereby making it possible for the bilge pump to draw clear and clean water for the service in the ejector 15.

50 At a suitable location in the line 13 and in open communication therewith is located a pumping cylinder 16 having movably positioned therein the plunger 4 and the pump piston 17, the plunger 4 may be connected in any suitable manner to the prime mover 3, in such a way that the plunger 4 will receive the required reciprocating motion, through an element 18, or any other device which will accomplish the purpose. On each side of the plunger and piston, 4 and 17, and located in the line 13 are suitably formed check valves 19 and 20.

55 The main suction inlet passage 10 is provided in this invention with suitably located openings 21 and 22 for the purpose of receiv-

ing in open communication therewith auxiliary suction lines 23 and 24 which may be made of flexible hose, or otherwise, and connected through suitable fittings 25 and 26 to valves 27 and 28, arranged for the purpose of allowing the suction to operate in either the bow or stern of the boat as may be desired, a third valve 29 being located in the suction inlet passage 10 below the openings 21 and 22 for the purpose of closing off the suction to the center bottom portion of the boat whenever desired.

The ejector casing 8 may be constructed in any manner suitable for the purpose, and have in open communication therewith a pressure gauge 30 for setting the relief valve, an air chamber 31 for relieving the pulsations of the pump and a relief valve 32 for taking all the surplus water that cannot pass through the ejector nozzle or orifice 33, a line 34 leads from the relief valve 32 as a surplus discharge. A hose member 35 is preferably attached to the outlet passage 11 for overboard discharge.

25 The lower end of the suction line 10 is fitted with a bilge suction strainer 36 of proper construction, while the free ends of the lines 23 and 24 are fitted with strainers 37 and 38 having a suitable number of holes located therein.

This invention provides a pumping system having three different suctions in different locations in the boat, and each one of the suctions will render useful service either separately or collectively as desired by the operator. Only one ejector will be required in this system.

It is readily apparent from the above description that the gases could be drawn from the stern of the boat by closing valves 28 and 29, or from the bow of the boat by closing valves 27 and 29. In case the bilge suction line 10 is desired to be used exclusively, the valves 27 and 28 should remain closed, or the bilge suction 10 and bow suction 24 could be used together by closing the valve 27 and opening the valves 28 and 29.

As a matter of fact, numerous operative elements can be made between the three suction lines 10, 23 and 24, by merely manipulating the valves 27, 28 and 29, the single ejector 15 accomplishing all of the desired results.

It will be understood that many changes and modifications may be made in the form of the embodiment of the invention within the scope of the following claim without departing from the spirit thereof.

What I claim is:

60 The combination with a marine vessel having an engine and a gasoline tank, of an ejector, a conduit leading directly from under the water outside the vessel to the nozzle of the ejector, two inwardly opening check valves in said conduit, a cylinder commu-

nicating with the conduit between the valves, an imperforate plunger in the cylinder, a conduit leading from the interior of the vessel to the suction chamber of said ejector, flexible branch conduits leading from the said interior conduit to the vicinity of said engine and tank, respectively, independently operable cut-off valves in the interior and branch conduits, and another conduit leading from the discharge end of said ejector to the exterior of the vessel.

In testimony whereof I affix my signature.

SOLOMON EDWARD AARON.
